UNITED STATES PATENT OFFICE.

PIERRE GANDILLON, OF TARBES, FRANCE.

WATER-CLOSET.

Application filed January 2, 1919. Serial No. 269,332.

To all whom it may concern:

Be it known that I, PIERRE GANDILLON, of Rue Sainte-Catherine No. 2, Tarbes, Hautes Pyrenees, France, engineer, have invented Improvements in or Relating to Water-Closets, of which the following is a full, clear, and exact description.

This invention has for its object to provide an improved range of compartment waterclosets operated on the automatic flushing system.

In the accompanying drawings:

Fig. 1 is a front elevation of a range of compartment water closets embodying the present improvements.

Fig. 2 is a horizontal section on the line *a—b* of Fig. 1.

Fig. 3 is a plan of the general structure.

Fig. 4 is a vertical cross section on the line *c—d* of Fig. 1.

Fig. 4^a is an elevational detail of the operable connection with the float.

Fig. 5 is a detail view of the flushing siphon.

Fig. 6 is a diagrammatic plan of the operating mechanism.

The improved range consists of a plurality of compartments with squat seats 1 discharging into suitably inclined fall pipes 2 from which the soil is discharged into a collector 3 after passing through siphons 4.

Upright open branches 5 and 6 are positioned opposite each compartment and permit of inspection of the siphon that serves the said compartment and the collector. The latter is cleansed automatically by periodic water flushes from an automatic flushing cistern 7 provided on the roof and furnished with a flushing pipe 8 that is ventilated at 9. The door of each compartment has for its hinge a rod 10 which extends through the roof and on which is fixed a lever 11 actuated by a spring 12 having a constant tendency to hold the door 13 opened as far as a stop 13'. Each compartment is cleansed automatically by water flushes caused automatically by the mere movement of its door.

For this purpose a flushing cistern 14 is provided on the roof of the structure immediately over each compartment, and in this cistern a siphon 15 is immersed whose long leg 16 ends in a flat nozzle 17 just over the squat seat. The siphons 15 are provided with a starting apparatus consisting of a branch with a seat upon which a

valve 18 is adapted to bear. This valve is operated by means of a bell crank lever 19 and a pull member 20 (furnished with a ring 21) which is connected to a lever 22 adapted to rock on a pivot 23. This rocking lever is held in a fixed position by a counter-spring 24. The two levers ending in beaks and cams, are so arranged that in the closing movement of the door the cams will be in contact, but will not act upon the valve 18, the ring 21 allowing of the return movement. But the opening of the door will cause the beaks to come in contact and actuate the bell-crank lever 19 so as to raise the valve 18, whereupon the siphon will be started and a flush will be produced.

All the flushing cisterns are supplied from a common water channel 25 with which they communicate through small holes 25' and which channel is supplied with water by a valve controlled supply pipe 26. The highest level of water in the automatic flushing cistern 7 is slightly lower than the water level in the common water channel which is situated in its turn slightly below the bend of the siphons. Urinals may be provided against the end walls of the compartmented structure, drawing their water supply from the common water channel and discharging their waste into the collector.

It is to be understood that the shapes, details, accessories, materials and dimensions of the range of waterclosets may be varied without departing from the nature of the invention. For instance the compartments, the water channels and the flushing cisterns may be made as a single structure of reinforced concrete.

Having now particularly described and ascertained the nature of my said invention and in what manner the same is to be performed I declare that what I claim is:

1. In an apparatus of the character described, a range of compartment water closets, flushing apparatus therefor, and mechanism associated with the doors of the compartments for normally holding the doors open and also associated with the flushing apparatus for automatically operating said flushing apparatus when the door opens.

2. In an apparatus of the character described, a range of compartment water closets, flushing apparatus for the water closets including a plurality of cisterns one for each water closet, a water channel com-

municating with the cisterns, supply means for the channel, valved siphons for controlling the flow from the cisterns, and mechanism for normally holding the doors of the compartments in open positions and associated with the valved siphons for automatically flushing the cisterns upon opening the doors.

The foregoing specification of my improvements in or relating to waterclosets, ¹⁰ signed by me this 2nd day of December, 1918.

PIERRE GANDILLON.
